UNITED STATES PATENT OFFICE.

LUTHER C. CROWELL, OF BROOKLYN, ASSIGNOR TO ROBERT HOE, STEPHEN D. TUCKER, THEODORE H. MEAD, AND CHARLES W. CARPENTER, OF NEW YORK, N. Y.

WEB-PRINTING MACHINE.

SPECIFICATION forming part of Letters Patent No. 508,918, dated November 21, 1893.

Application filed August 22, 1892. Serial No. 443,689. (No model.)

To all whom it may concern:

Be it known that I, LUTHER C. CROWELL, a citizen of the United States, residing at Brooklyn, county of Kings, and State of New York, have invented certain new and useful improvements in Web-Printing Machines, fully described and represented in the following specification and the accompanying drawings, forming a part of the same.

10 In newspaper printing it is often desirable to print a paper or part of a paper in colors, while it is undesirable to further increase the size and complication of rapid web printing machines by additional printing mechanisms for such color printing, and the cost of such machines of high capacity and the extra floor space required, prevent the general use of separate color printing machines. In all printing offices, moreover, in which multicolor 20 printing is ever desirable, the advantages of a construction enabling such color printing from printing mechanisms the full capacity of which is available for web perfecting, will readily be recognized.

25 The object of the present invention is to provide an improved construction of web printing machines by which the full capacity of the printing devices may be utilized for web perfecting or multiple impressions for color printing be taken therefrom, and I attain this object by combining with a plurality of web printing mechanisms capacitated to print and perfect a plurality of webs, web controlling devices co-acting therewith 35 to present a web of less width than the capacity of the printing surfaces of some or all of the printing devices, so that the printing mechanisms may be used for perfecting a plurality of full width webs or printing in colors 40 on a web of less than full width as desired.

While I claim such a combination broadly, and my invention includes a construction in which a plurality of web printing mechanisms are combined with web controlling devices so as to print and perfect a plurality of webs or to co-act in printing in multiple impressions on a web of less than full width, whether upon a single such narrow web or a

plurality of narrow webs simultaneously, I 50 am enabled by my invention to provide a construction by which a plurality of full width webs may be perfected, or a plurality of webs of less than full width printed, one of which webs of less than full width may be 55 perfected and the other printed in colors, or both webs printed in colors. I am thus enabled to provide a construction which will print and perfect a plurality of full width webs at high rates of speed, or may be used 60 to produce at correspondingly high rates of speed the most desirable products in color printing, and under my invention I intend to include also, broadly, such a construction.

It is evident that my invention broadly 65 considered may be applied in connection with web printing mechanisms of any suitable form, that the web controlling devices for guiding the web for color printing may be of any suitable construction, and that many different arrangements of the two may be made 70 in accordance with the result desired.

In the accompanying drawings forming a part of this specification, I have shown constructions embodying my invention in two of 75 the preferred forms, certain features in which constitute specific parts of my invention, and from a detailed description of these constructions, the application of my invention in other constructions will be obvious to those skilled 80 in the art.

In the drawings: Figure 1 is a longitudinal sectional diagram taken inside the frame of a construction embodying my invention in one of its preferred forms, as applied in 85 connection with two web perfecting mechanisms of a common form, each having two sets of type and impression cylinders and so combined as to permit the perfecting of two webs, each the full width of the machine, or the 90 printing of a plurality of narrow webs, with a number of impressions on one or both sides, this figure showing the course of the two full width webs in perfecting simply, that is, printing one impression on each side. Fig. 95 2 is a similar view showing the course of the webs in printing two webs of less than full width, one being perfected simply and the

other printed with five impressions on one side and one on the other. Fig. 3 is a similar view showing the course of the latter web alone. Fig. 4 is a plan view corresponding to Fig. 2. Figs. 5 to 8 show another construction embodying my invention. Fig. 5 is a view similar to Figs. 1 to 3, showing the course of the webs in printing two webs of less than full width, one web being printed with four impressions on one side and one on the other, and the other with three colors on one side. Figs. 6 and 7 are similar views showing, respectively, the course of the former and latter webs alone. Fig. 8 is a plan view corresponding to Fig. 5.

Referring now to Figs. 1 to 4, A, B, and C, D, are the two sets of type and impression cylinders forming one full width web perfecting mechanism, and E, F, and G, H, the corresponding sets of type and impression cylinders of a second full width web perfecting mechanism, A, C, and E, G, being the respective type cylinders and provided with inking mechanisms I of any suitable form. These web perfecting mechanisms may be provided with separate deliveries if desired, or may constitute each a separate machine, the web being led from one to the other in color printing, but they are shown as forming a duplex web machine and having a common delivery K which may be of any suitable form capacitated to deliver products of different widths, that shown having the pair of longitudinal folders and the slitter commonly employed in double width machines, each half of the divided web, single or two ply, being folded by its respective folder. With these web perfecting mechanisms, I combine in the construction shown in Figs. 1 to 4 a web reverser and transerrer L and a web reverser M. These parts may be of any suitable construction, so that the web transerrer and reverser will operate to transfer the web from one end of the type and impression cylinders to the opposite end and reverse it simultaneously, and the reverser operates to reverse the web without transferring. As shown, the web transerrer and reverser L is a common web turner consisting of two converging bars, and the web reverser M is of the common form consisting of three bars arranged to reverse the web without transferring, such a web reverser being shown and fully described in my Patent No. 212,444 so as to need no further description here.

The paths of the webs are as follows: In perfecting two full width webs, as shown in Fig. 1, the first web x is led around conducting rolls 1, 2 and downward between the first type and impression cylinders A, B, then around cylinder B and upward between the second type and impression cylinders C, D, whence the perfected web passes to the delivery mechanism K. The second web y passes upward between the first type and impression cylinders E, F of the other web perfecting mechanism, then around the impression cyl-

inder H and downward between it and the type cylinder G, whence the perfected web passes around conducting rolls 3, 4 to the delivery mechanism K, where it is associated with the first web forming a two ply web which is divided longitudinally into two narrow webs which are led to their respective longitudinal folders. In printing two half width webs, one perfected simply, or printed in but one color on each side, and the other in five colors on one side and one on the other, as shown in Fig. 2, the first mentioned web y is led over one end of the type and impression cylinders E, F, and G, H, in the usual manner. For convenience this web is shown as led over the rear ends of these cylinders, and the web x over their front ends, but it will be understood that this may be varied. In printing the web x in five colors on one side and one on the other as shown in Figs. 1 and 2 the web is led to and between the rear ends of the cylinders A, B, and C, D in the usual manner, then passes around the impression cylinder D to and under the conducting roll 5 and around web reverser and transerrer L, by which the web, perfected at the rear ends of the cylinders A, B, and C, D, is reversed and transferred to the front of the machine, thence over the cylinder B between it and type cylinder A, receiving from the front ends of cylinders A, B a second color on the side which received the second or perfecting impression, thence directly to the type and impression cylinders E, F, whereby a third color is imprinted on this side, thence around cylinder F and between it and impression cylinder H past the web transerrer and reverser L between cylinders D, E, and over conducting roll 6 to and around the web reverser M, by which the web is reversed without transferring, thence over the conducting rolls 7, 8 to and between the cylinders C, D, whereby a fourth color is imprinted by the front ends of these cylinders, thence directly to the cylinders G, H, receiving a fifth color, whence the web now printed with five colors on one side and one on the other passes over the conducting rolls 3, 4 to the delivery mechanism K and is folded by one of the longitudinal folders thereof, while the other web y abreast web x on the rear of the machine is folded by the other longitudinal folder. In this construction, the five colors are upon the side which receives the second or perfecting impression, but it will be understood that, if a simple transerrer consisting of the usual two parallel bars be substituted for the reverser and transerrer L, the same product may be obtained except that the five colors will be upon the side which receives the first impression from the cylinders A, B.

It is evident that various other products may be produced by simply varying the path of the web. For instance, if it be desired to print the web x with only four colors on one side and one on the other the web will be led to and between cylinders A, B and C, D,

at the rear of the machine, as before, thence directly to the cylinders G, H, around cylinder H, to and around roll 5 and the transferrer L, by which it is transferred to the front 5 of the machine, thence to and between cylinders A, B, and directly to the cylinders E, F, and out over rolls 3, 4, to the delivery mechanism. If three colors on one side and one on the other of web x be desired, the 10 web, printed and perfected by the cylinders A, B, and C, D, will be led, at the rear of the machine, to and around the web reverser and transferrer L and thence, at the front of the machine, directly to the web reverser M and 15 to cylinders C, D, and G, H, and out as above described, or the reversal by the reverser M may be omitted and the web led from the web reverser and transferrer L directly to the cylinders C, D, and G, H. If a web print- 20 ed in four colors on one side only be desired, the web x at the rear of the machine may be led from cylinders A, B, around the cylinder B to the reverser M, thence to the cylinders C, D, thence about the web reverser and 25 transferrer L and to the front ends of the cylinders C, D, and G, H.

Many other variations may be made and many modifications in the construction shown 30 may readily be devised by those skilled in the art.

In Figs. 5 to 8 I have shown a modification employing two perfecting mechanisms of the same kind as shown in Figs. 1 to 4 in combination with two web reversers and transferrers, the construction being shown in these 35 figures as printing and delivering associated together two webs of less than full width, the web x being printed with four colors on one side and one on the other, and the web y 40 with three colors on one side only. The path of the webs in this construction is as follows: The web x is led to the type and impression cylinders A, B, and C, D at the rear of the machine, as previously described, thus being per- 45 fected, thence to the cylinders G, H and over the conducting roll 9 and web reverser and transferrer N, by which the web is reversed and transferred to the front of the machine, thence about the impression cylinder H and 50 under the conducting rolls 10, 11 to cylinders A, B, thence to cylinders E, F and out over the roll 12 to the delivery mechanism K, printed with four colors on one side and one on the other. The web y is led to the cylinders E, 55 F, at the rear of the machine, thence around the cylinder F, over the reverser and transferrer O, by which the web is reversed and transferred to the front of the machine, thence over the conducting roll 13 to the cylinders 60 C, D, and G, H and out under rolls 3, 4, to the delivery mechanism K, printed in three colors on one side only and associated with the web x. If two webs, each printed in three colors 65 on one side and one on the other, are desired, the web x will be led to the cylinders A, B, and C, D, and perfected thereby, thence led to the cylinders G, H, then reversed and trans-

ferred to the front of the machine by the reverser and transferrer N and led about the impression cylinder F and between it and cylinder E. The web y will be led to the cylinders E, F, at the rear of the machine around the cylinder F to the reverser and transferrer O, thence to cylinders A, B, and C, D, and G, H, at the front of the machine and out, associated with the web x as before. 70 75

It will be understood that, in the production of all the products described, the webs may be led to the opposite ends of the cylinders from those stated, and that the description of the webs as led to the rear or front is only for convenience. 80

Many other constructions embodying my invention may readily be devised by those skilled in the art, such constructions being 85 varied in accordance with the result desired. It will be understood, therefore, that my invention is not to be limited to any of the specific arrangements shown, nor to the specific form 90 of any of the printing mechanisms or of the web controlling devices combined therewith, but that the form and arrangements of the parts may be varied widely without departing from my invention.

It is evident that the web controlling devices may readily be located as shown so as not to interfere with the lead of the webs in perfecting, enabling the construction to be used for web perfecting or color printing without other change than the lead of the web, but 100 it will be understood that this is not absolutely essential, but that the invention may be embodied in a construction in which the web controlling devices must be removed or thrown out of position for web perfecting. 105

It will be understood that the web perfecting mechanisms combined with web controlling devices to embody my invention may form independent machines, or may be combined in a single machine printing from a plurality 110 of webs, as shown. The mechanisms shown are adapted to perfect double width webs or to print in colors single width webs, and it will be understood that the term "half width" and "less than half width" used herein refer 115 not to the size of the page but to the capacity of the printing mechanisms, and the invention may be embodied in machines printing webs of any width according to the products desired. 120

What I claim is—

1. The combination with a plurality of web perfecting mechanisms, of web controlling devices co-acting therewith to present a web of less than full width to different parts of the same printing devices, whereby a plurality of impressions may be printed upon the same side of a single web from the different mechanisms, substantially as described. 125

2. The combination with a plurality of web perfecting mechanisms, of web controlling devices co-acting therewith to present a web of less than full width to different parts of each of the printing devices, whereby two webs of 130

less than full width may be printed and a plurality of impressions be printed on the same side of one or both of the webs, substantially as described.

5 3. The combination with a plurality of web perfecting mechanisms arranged to co-act in printing a web of less than full width, of a web transferrer coacting therewith to present said web to different parts of the same printing devices, substantially as described.

10 4. The combination with a plurality of web perfecting mechanisms arranged to co-act in printing a web of less than full width, of a web

transferrer coacting therewith to present said web to different parts of the same printing devices, and a web reverser coacting therewith to reverse the web between impressions, substantially as described.

15 In testimony whereof I have hereunto set my hand in the presence of two subscribing witnesses.

LUTHER C. CROWELL.
